UNITED STATES PATENT OFFICE.

EUSTACHE AUGUSTE CRESSON, OF PARIS, FRANCE.

CALENDAR-WATCH.

SPECIFICATION forming part of Letters Patent No. 650,826, dated June 5, 1900.

Application filed May 14, 1896. Serial No. 591,495. (No model.)

To all whom it may concern:

Be it known that I, EUSTACHE AUGUSTE CRESSON, of the city of Paris, France, have invented a Combined Watch and Perpetual Calendar, (for which I have obtained Letters Patent in France for fifteen years, dated June 17, 1895, No. 248,206; in Belgium for fifteen years, dated June 17, 1895, No. 116,111; in England for fourteen years, dated August 13, 1895, No. 15,245, and in Switzerland for fifteen years, dated August 13, 1895, No. 11,020,) of which the following is a full, clear, and exact description.

My invention relates to a combined watch and perpetual calendar; and it consists, essentially, of a case containing the watch-movement and inclosed within a triple ring rotatable about the case and the members of the band and case bearing the various inscriptions of the perpetual calendar.

Reference is to be had to the accompanying drawings, forming part of this specification, wherein is represented a keyless watch combined with a perpetual calendar, the calendar being of the kind which forms the subject of previous Letters Patent of the United States of America, No. 452,450.

Figure 1 is a face view of the combined watch and calendar, part of the band being broken away. Fig. 2 is an edge view of the watch, showing the revolving triple ring in vertical section taken through the axis of the pendant. Fig. 3 is a back view of the combined watch and calendar. Fig. 4 shows the band developed in the flat and the numbers inscribed on its periphery.

The same letters denote like parts in all the figures.

My invention consists, essentially, of a watchcase *a* for the watch-movement and inclosed within a calendar-case rotatable thereon, the three members of the calendar-case being a band *b'* and bezels *b²* *b³*. The band bears upon its periphery the numbers by which to find the key whereby to ascertain the name of the first day of any year and carries the pendant *c* and the push-piece *d* for setting the hands. The bezels *b²* *b³* are adapted to be snapped upon the ring *b'* and are adapted to turn freely thereon when in place. Both of these bezels bear the names of the days of the week, the one in direct and the

other in reverse order, as shown in Figs. 1 and 3. The watchcase *a* bears upon the side corresponding to the watch-dial the days of the month and upon its opposite side, Fig. 3, the names of the months and the three numbers "20," "48," "76," the use of which will be hereinafter explained. The pendant *c*, fixed to the band *b'*, carries the winding-stem *e*, which is turned by the knob *f* and terminates in a key-socket *g*, the winding-stem being free to turn in the pendant and also to be moved longitudinally in order that the key *g* may engage with the squared end *h* of the winding-post, 65 which is within the case *a*, the longitudinal movement of the stem *e* being limited by shoulders. The push-piece *d* is pressed and normally maintained outward by a flat spring *i*. This spring is adapted to bear upon the 70 hand-setting push-piece *j*, which projects but a slight distance from the case *a*, so as not to interfere with the rotary movement of the watchcase with relation to the calendar-case. Marks should be provided on the watchcase 75 and revolving ring to enable the key *g* to be at once brought opposite the winding-post *h*, in which position the figure "XII" of the dial will be opposite the pendant, as usual; but the key *g* may be held in engagement with 80 the winding-post *h* by means of a spring suitably arranged.

To use the calendar, the winding-stem *e* is disengaged from the winding-post *h*, so that the watchcase is free to revolve within the 85 calendar-case formed by the parts *b'* *b²* *b³*.

This combined watch and perpetual calendar thus serves for indicating both the time and the day of the week corresponding to any day of the month.

In order to use the calendar, it is only necessary, as described in my said former patent, in the case of normal years to place the name of the month opposite the name of the first day of the year and then to read off the name 95 of the day, which will be found above the day of the month given. Thus to find the day of the week of the 13th of June, 1895, it being known that the first day of the year 1895 was Tuesday, turn the sections of the calendar-case with relation to each other until the section of the case *a* containing June is opposite the section "Tuesday" on ring *b²*, and I then find at the other side of the watch on

the division of ring b^3 opposite "13" the name "Thursday."

In the case of leap-years the mode of use is slightly different, (except for the months of 5 January and February,) the month selected being placed opposite the name of the second day of the year. Thus to find the day of the week of the 7th of March, 1896, it being known that the first day of the year 1896 was 10 Wednesday, the division of case a bearing the name "March" is placed opposite the division "Thursday" of ring b^2 , and then at the other side find the division of ring b^5 opposite the 17th day of the month, which bears the 15 name "Tuesday."

To find the name of the first day of any year in the nineteenth century, subtract from the number formed by the two last or right-hand figures of the year in question the greatest of the numbers ("20," "48," "76," found on the back of the watchcase,) which is less than the said number, and then find in the movable band b' the number which corresponds to the remainder, and the day of the week 20 which is found in the same division on one of the bezels will be the day sought. If the number formed by the last two figures of the year is below twenty, add eight and then proceed as above. As the band b' may be 25 shifted relatively to the bezels b^2 b^3 , the numbers "20," "48," "76" may be used beyond the present century.

It should be understood that the above-described type of calendar is given merely by 30 way of example and that any other combination may be used.

I claim—

1. In a combined calendar and stem-winding watch, the combination of a watch-movement-containing case, a band capable of rotation independent of said case, a longitudi- 40

nally-movable winding-stem carried by said band, so that the stem can be engaged with and disengaged from the winding-post of the winding mechanism, and a hand-setting stud 45 movable with the watch-movement-containing case and independent of the movable band and adapted to be actuated by a push-piece carried on the movable band and disconnected from the hand-setting stud and 50 watch-movement case, as specified.

2. In a combined perpetual calendar and stem-winding watch, the combination of a watch-movement-containing case, a calendar-case rotatable around the watch-movement-containing case, said calendar-case comprising a rotatable band with independently-rotatable bezels having indices thereon, the said band constituting the edge of the case and having indices which coöperate with the 60 indices upon the bezels and upon the face and back of the watch-movement-containing case, a longitudinally-movable winding-stem carried by said band, said winding-stem being normally out of engagement with the 65 winding-post of the winding mechanism and adapted to be forced into operative engagement therewith, a hand-setting stud carried by and movable with the watch-movement-containing case and adapted to be actuated 70 by a push-piece carried by the movable band, said push-piece being disconnected from the hand-setting stud and watch-movement-containing case, substantially as and for the purposes specified.

The foregoing specification of my combined watch and perpetual calendar signed by me 75 this 16th day of April, 1896.

EUSTACHE AUGUSTE CRESSON.
